UNITED STATES PATENT OFFICE

HUGH NAIL LEIPER, OF OKLAHOMA CITY, OKLAHOMA, ASSIGNOR TO NEW STATE ICE COMPANY, OF OKLAHOMA CITY, OKLAHOMA, A CORPORATION OF DELAWARE

ICE CREAM CONTAINER

Application filed August 13, 1930. Serial No. 475,038.

This invention relates to folding carton and particularly to a carton of general triangular cross section for packaging ice cream or similar frozen products.

Its principal objects are three-fold, first, to provide a carton of the type described that can be shipped flat; secondly, to construct a carton that shall be leak-proof in relation to its contents when the latter are in semi-liquid state; and finally, to provide a carton which may be peeled from the contained block of cream, cleanly and without disintegrating the thinner portions of the block.

Other objects of the invention will appear as the following description of a preferred embodiment thereof proceeds.

In the drawings which accompany and form part of the specification and in which the same characters of reference have been used throughout the several figures to denote identical parts:

Figure 1 is a perspective view showing the carton partly peeled or unfolded from the contained block of ice cream;

Figure 2 is a cross section through the carton;

Figure 3 is a section taken along the line 3-3 of Figure 2;

Figure 4 is a perspective view of the carton ready for filling;

Figure 5 is a plan view of the blank folded flat, as for shipment; and

Figure 6 is a plan view of the blank in expanded form.

Referring now in detail to the several figures, and comparing Figure 6 with Figure 2, it will be noted that the carton has the cross sectional shape of a truncated isosceles triangle, the base and side portions of which are rectangular as indicated at 1, 2 and 3, in Figure 6, the end portions 4, 5 and 6 being of generally triangular shape and lying in superposed position when the carton is folded.

Instead of coming to an acute dihedral edge at the top as the most triangular cartons do, the present carton is formed with a flat top face 7, and one pair of the opposite end faces is formed with tabs 8 and 9 which tuck into the slot formed at the end

edges 10 and 11 of the top face 7, when the carton is folded, thus securing the end faces in superposed, enfolded relation to the carton.

On account of the frustrated shape of the cross section of the folded carton, it is obvious that one pair of the triangular end faces, 6 will be similarly shaped while the pair of end faces 5 bearing the tabs is similarly truncated by means of a score 12 differentiating the tabs from the box of said end faces.

The blank is put together preferably at the time and place of its manufacture by means of a tab 13 which is pasted over the base 2 as shown in Figure 5. To enable the carton with its ends thus joined to be packed flat for shipment, the side face 3 together with the adjacent end face 6 is provided with a score or weakened line 14 permitting the said side and end faces to be folded as shown at Figure 5, the score representing the edge of the carton when so folded.

When the carton is set up for filling, the triangular end faces at one end are folded together so as to over-lie one another, the edge of one coinciding with the score or line of fold 15 which demarks the end faces from the base and side faces. Since an edge of each end face coincides with the lines of fold between the end faces and the base and side faces, it is clear that a continuous joint is formed around the end of the carton which is leak-proof except at the corners. As has been stated, a tight fit is assured at the edge 11 of the top face of the tucking in of the tab 9. The carton with one of its ends thus closed is shown in Figure 4 and the contents are filled into the carton from the open upper end, preferably while in semi-liquid state. The substantially liquid tight nature of the joint between the end of the carton and the base and sides altogether prevents leakage of the semi-solid contents.

After the carton has been filled the freezing of the contents is completed, the contained block of ice cream or other frozen product becoming solid and being in solid condition when removed from the carton.

The manner of removing the ice cream from the carton is quite different from the mode of filling it. In the former instance as has been described the carton is filled at 6 one end as will be suggested by Figure 4. When the contents are to be removed, this is done by slipping a knife between the flap 13 and the face to which it is attached so as to break the adhesive and permit the carton 10 to be opened at the flap. It will be obvious from Figure 1 that the side walls of the carton are merely peeled from the ice cream and that the two layers of the end walls are not even in contact with the ice cream and therefore, 15 come readily away. The two end faces which are in intimate contact with the ice cream are pulled outwardly by grasping the tabs 9. In ordinary triangular ice cream packages, in which the top of the carton 20 comes to an acute dihedral angle, the attempt to peel away the carton adjacent its top edge from the ice cream results in the ridge of ice cream being broken away by adherence to the carton and by reason of its weak cohesion due to the thinness of its cross section at this point. By doing away with a sharp dihedral angle at the top of the carton and substituting therefor, the flat face 7, the angle between the side and top face becomes 25 obtuse and not acute and therefore offers a resistance to disintegrating which is greater than the frictional adhesion of the ice cream to the carton. In consequence, the carton peels away clean and leaves a perfect block, none of the cream adhering to the carton.

When the carton has been peeled away from the ice cream on all sides except the base, the carton is tipped upon the plate 40 which is to receive the cream, so that the latter falls out in an unbroken block with none of the ice cream adhering to the walls of the carton.

45 While theoretically the apex of the innermost end face is too long to permit opening the carton in the manner described, yet in practice the carton is capable of slight end-wise deformation so that it is entirely feasible for the carton to be peeled from the ice cream in the manner set forth.

50 It is obvious that the principle of the invention is such as to admit of its carrying out in other forms than that specifically described by way of example.

55 What I claim is:

Folding carton of trapezoidal cross section comprising a wide base, narrow top and convergent sides, end faces extending integrally from the edges of the base and both 60 sides and foldable into super-posed relation, forming substantially leak-proof ends, each outer-most end face having a tuck flap tucking into the crack formed between the top 65 and the other two super-posed end faces.

there being a flap closing the joint between one side and the base integral with one of said members and pasted to the other.

In testimony whereof I affix my signature.

HUGH NAIL LEIPER.
